(57) **CLAIM**

I claim the ornamental design for a theft-preventing license plate frame, as shown and described.

DESCRIPTION

FIG. 1 is a perspective view of a theft-preventing license plate frame shown in its position of use, showing my new design; FIG. 2 is a rear perspective view thereof, showing a hinged element in an extended position;

FIG. 3 is a front elevational view thereof;

FIG. 4 is a rear elevational view of FIG. 2;

FIG. 5 is a left-side elevational view of FIG. 2, the right-side elevational view being a mirror image thereof;

FIG. 6 is a top plan view of FIG. 2;

FIG. 7 is a bottom plan view of FIG. 2; and,

FIG. 8 is a rear perspective view thereof, showing the hinged element in a retracted position.

The broken lines showing a vehicle in FIG. 1 depict environmental matter and form no part of the claimed design.

The license plate frame is shown on an enlarged scale in FIGS. 2-8.
